UNITED STATES PATENT OFFICE.

LYMAN CARRIER, OF JOLIET, ILLINOIS.

DETECTOR-BAR FOR RAILROAD-SWITCHES.

SPECIFICATION forming part of Letters Patent No. 703,537, dated July 1, 1902.

Application filed April 24, 1902. Serial No. 104,582. (No model.)

To all whom it may concern:

Be it known that I, LYMAN CARRIER, a citizen of the United States, residing at Joliet, in the county of Will and State of Illinois, have 5 invented certain new and useful Improvements in Detector-Bars for Railroad-Switches; and I do declare the following to be a full, clear, and exact description of the invention, such as will enable others skilled in the art to 10 to which it appertains to make and use the same.

This invention relates to certain improvements in detector-bars for railroad-switches, adapted to prevent movement of the switch while the wheels of a car are on the movable 15 rails or rails adjacent to the switch-rails.

The object of the invention is to provide a detector-bar which is simple of construction, durable and efficient in use, and comparatively inexpensive of production and in which 20 provision is made for shielding the parts from access of dust, dirt, &c., and from casual injury.

With the above and other objects in view, which will readily appear as the nature of 25 the invention is better understood, said invention consists in certain novel features of construction and combination and arrangement of parts, which will be hereinafter fully described, defined in the appended claims, and 30 illustrated in the accompanying drawings, in which—

Figure 1 is a top plan showing the application 35 of the invention. Fig. 2 is a longitudinal section through the detector-bar and stationary bar, showing in full and broken lines the two extremes of adjustment of the detector-bar. Fig. 3 is a side elevation. Fig. 4 is a cross-section on line 4 4 of Fig. 2.

Referring now more particularly to the 40 drawings, the numeral 1 represents an ordinary railroad-rail resting on cross-ties 2.

A bar 3 is secured to the ties at the side of the rail 1 in any preferred manner. Above this bar 3 is arranged a bar 4, which may be 45 termed the "detector-bar" and which has journaled therein rollers 5, which roll upon the bar 3, and thereby support said detector-bar. The bar 4 is thus mounted to reciprocate or travel longitudinally on the stationary 50 bar 3 and is provided at one end with a rod 6 for connection with any ordinary switch-

stand mechanism, so that whenever the switch is operated it will through the medium of said rod move the bar 4 endwise in either direction.

The bar 3 is formed in its upper edge with 55 undulating surfaces 7, which extend only a short distance, far enough to accomplish the desired object. These undulating surfaces are adapted to receive the rollers 5 as the bar 4 is moved back and forth, so that when the 60 detector-bar is moved forward, as when the switch is moved in one direction, the rollers will stand upon the apexes of the undulating surfaces and elevate said detector-bar, so that it will project above the rail 1 and indicate 65 the position of the switch. When the car-wheels are standing on the railroad-track on its part adjacent to the detector-bar 4, the car-wheels will prevent the detector-bar and the switch, to which it is connected, from being moved, as when the detector-bar is moved from the full-line position shown in Fig. 2 it must necessarily be elevated, which is impossible while the car-wheels stand over the 70 detector-bar, so that the switch cannot be 75 moved and run the cars off the track while they are over the detector-bar. It is intended that the detector-bar 4 shall be long enough to extend a considerable distance in either direction from the switch, so as to prevent turning of the switch some time before a train reaches the switch, and it is designed that when the detector-bar is given its full throw in either direction it will be down out of the 80 way of a passing train. It is only when a train 85 is over the detector-bar that the switch is prevented from being turned in either direction, as the detector-bar is only elevated just while the switch is being turned in either direction.

As shown, the detector-bar is held from outward displacement between the rail and suitable guides 8 and is preferably channeled or of inverted-U form, so that it will serve as a hood or shield to inclose the bar 3 and rollers and prevent access of dust, dirt, or any foreign substance or obstructions likely to clog 95 the rollers and interfere with the proper operation of said detector-bar and also to protect the parts from injury by exterior shocks or blows.

From the foregoing description, taken in connection with the accompanying drawings,

it is thought that the construction, mode of operation, and advantages of my improved detector-bar will be readily apparent without requiring a more extended explanation.

5 Various changes in the form, proportion, and the minor details of construction may be resorted to without departing from the principle or sacrificing any of the advantages of this invention.

10 Having thus described my invention, what I claim as new, and desire to secure by Letters Patent, is—

15 1. The combination with a rail; of a bar fixed at the side of the rail, a channeled bar movably mounted and inclosing the top and sides of the fixed bar, one of said bars having an undulating surface and the other rollers to traverse said fixed bar whereby the second bar is adapted to rise and fall when adjusted 20 lengthwise of the fixed bar, and means for

imparting an endwise movement to the upper bar, substantially as specified.

2. The combination with a rail, of a bar fixed at the side of the rail and having an undulating surface, a second bar movably 25 mounted above the fixed bar and having rollers supporting it on said fixed bar, said second bar being channeled to inclose the rollers and top and sides of the fixed bar, and means for imparting an endwise movement to the 30 upper bar, substantially as and for the purpose set forth.

In testimony whereof I have hereunto set my hand in presence of two subscribing witnesses.

LYMAN CARRIER.
